DEVICE FOR DISTRIBUTING DUSTING MATERIAL

Martin Berthold Rausch, Frechen-Buschbell,
Germany

Application July 7, 1950, Serial No. 172,417

Claims priority, application Germany
July 18, 1949

2 Claims. (Cl. 275—8)

1

The invention relates to a device for distributing material adapted to be spread out and more particularly to a manure distributor provided with a portable or travelling centrifugal disc rotating around a vertical axis to which the dusting material is fed from a store tank arranged above. Such distributors of dusting material are known e. g. as lime distributors, liquid manure spreaders and the like. All these distributors have the disadvantage that the width of the strewed surface changes with the centrifugal speed and the weight of the dusting material. A uniform or a desired periodically unequal strewing of limited surfaces cannot be obtained with such devices.

The invention removes this disadvantage there-by that the centrifugal disc rotating in a horizontal plane is surrounded along its entire circumference by a rebounding wall arranged preferably vertically and reversing the dusting material flung against it by the centrifugal disc in a horizontal or nearly horizontal plane from its flight path to the surface to be strewed. By this rebounding wall the surface to be strewed is exactly limited. The rebounding wall may also have the shape of a cap or hood closed on the upper side to avoid that finely pulverized dusting material is upwardly spread. Naturally the speed of rotation of the centrifugal disc must be chosen high enough to cause the dusting material to abut against the rebounding wall so that it is stopped in its flight path and is reversed preferably downwardly.

A further feature of the invention is to shape the rebounding wall so that it is composed of two curved or arcuate portions intersecting each other or passing into one another, whereby an elongated shape results which is symmetrical with respect to the short axis and whose longitudinal axis extends across the direction of motion. If the rebounding wall surrounding the centrifugal disc should be circular and concentric to the axis of the disc the dusting material would form a dam of troughlike cross-section on the surface to be strewed extending in the direction of motion. This dam would be the lowest in the middle and increase uniformly toward the two sides of the strip to be strewed. Such periodically unequal distribution of the dusting material, if desired, may be important for certain technical purposes but is not suitable for the distribution of artificial manure. Artificial manure must be distributed absolutely uniformly over the surface to be strewed. Therefore, it is necessary to give to the rebounding wall the mentioned elongated shape, the acute crests formed on the ends of the

longitudinal axis limiting the lateral edges of the surface to be strewed in the direction of motion.

An exactly uniform distribution of the dusting material reversed from its flight path by the rebounding wall to the surface to be strewed results preferably thereby that the rebounding wall receives equal quantities of dusting material within the reach of equal sectors related to the center of the disc or limited by tangents of the disc.

If it is required to strew e. g. a rooflike dam which should be highest in the middle of the surface to be strewed and decrease uniformly toward the lateral edges of said surface a corresponding shape of the rebounding wall may be realized. It is of importance for all embodiments of the idea of the invention that the dusting material delivered by the centrifugal disc in the horizontal direction is caught by a rebounding wall surrounding the disc on all sides and is reversed from its horizontal flight path toward the surface to be strewed, a uniform or a desired periodically unequal distribution of the dusting material on the surface to be strewed resulting in each case from the shape of the rebounding wall.

For the purpose to improve the uniform distribution it is suitable to supply the dusting material to the centrifugal disc in a uniform granulation and with uniform allotment. Therefore, a grinding mill may be provided coaxially with the centrifugal disc between the store tank of the dusting material and the centrifugal disc. After being preliminarily crushed in the store tank e. g. by worms working in opposite direction and fed into the grinding mill the dusting material is ground between a rotating grinding cylinder and a stationary mill casing and transmitted to the centrifugal disc angularly and concentrically e. g. over a conical grinding cylinder. In this way the centrifugal disc is always charged on every point of its circumference with equal quantities of dusting material of uniform granulation.

The drawing shows by way of example one embodiment of the invention which now is to be described.

Fig. 1 is a top plan view of a distributor for dusting material constructed according to the invention.

Fig. 2 is a vertical transverse section through Fig. 1, and

Fig. 3 illustrates theoretically the construction of the curvature of the rebounding wall.

A centrifugal disc e rotating around a vertical axis e^1 is supported in a manner known per se by a bogie wagon g drawn by a fore carriage h

with steering knuckles. Naturally also other driving and supporting means may be used e. g. a three-wheel vehicle in which the strewing device is arranged between the leading wheel and the hind axle; in this case the width of the vehicle may be smaller in spite of a big surface to be strewed.

The centrifugal disc *e* is continuously charged with dusting material from a supply hopper *a* by means of feeding rolls *b*, *c* and is driven by the traversing wheels of the bogie wagon or by any other suitable means. According to the invention the centrifugal disc *e* is surrounded by a rebounding wall *f* which, in the shown embodiment, has a vertically arranged flange and a hood-like cover, preferably integral with said flange. The dusting material horizontally delivered from the centrifugal disc *e* is stopped in its flight path by the said rebounding wall *f* and reversed downwardly in a vertical direction onto the surface to be strewed.

For the purpose of a uniform distribution of the dusting material the rebounding wall *f* has an elongated shape, the longitudinal axis being directed approximately across the direction of motion. The curvature of the rebounding wall is constructed in that way (Fig. 3) that the strip of the surface to be strewed is divided into zones by parallel lines *i* running in the direction of motion and that radial lines are drawn from the center of the disc *e* or, more suitable, tangential lines *k* are drawn from the circumference of the disc *e*, said radial or tangential lines including equal angles *m*. These lines correspond to the path in which the dusting material is strewed when leaving the disc *e*. The section points of the lines *i* and *k* are the points through which the theoretical curvature passes. As the dusting material does not leave the centrifugal disc *e* in a radial but in a tangential direction preferably the lines *k* run tangentially with respect to the circumference of the disc *e*. If the surface to be strewed should be covered with a uniform layer of dusting material the zone formed by the lines *i* are of an equal width. In Fig. 3 the entire circumference is divided into 24 equal angles so that the lines *k* form 24 sectors, and in the region of each of these sectors an equal quantity of dusting material is delivered at each time. The zones limited by the parallel lines *i*, therefore, receive in front and behind in the direction of motion a charge of dusting material so that the number of zones is half the numbers of the angles. Consequently 12 longitudinal zones are provided corresponding to 24 angles of division. In combination with twelve angles of division six longitudinal zones and in combination with thirty-six angles eighteen longitudinal zones must be provided. As in such construction of the curvature between each two parallel lines *i*, i. e. on each longitudinal zone an equal quantity of dusting material must be supplied, there is taken care for a uniform distribution of the dusting material over the entire width of the surface to be strewed provided the lines *i* have an equal distance from each other.

If an irregular distribution of the dusting material is desired it is only necessary to render the longitudinal zones of different widths, i. e., to draw the parallel lines *i* in a different distance from each other while the angles *m* remain equal, so that a certain equal quantity of dusting material is supplied to zones or strips of different width, the width of the single zones corresponding to the desired degree of irregular distribu-

tion. In that way practically every desired periodical form of distribution may be realized. Naturally the curvature of the rebounding wall *f* changes corresponding to the distances between the parallel lines *k*.

For reduction of the invention to practice, it suffices generally to draw the lines of division *i* radially from the center of the disc *e*, as different experiments have shown, thereby simplifying the construction. A still usable shape may also be obtained even if the curvature is substituted by an approximate arc of circle.

Between the supply hopper *a* and the centrifugal disc *e* a grinding mill *d*, *d*¹, *d*² may be provided coaxially with the disc. The dusting material is preliminarily crushed in the store tank by worm-like rolls *b* and *c* rotating in opposite direction and serving simultaneously as feeding rolls, and is then delivered into the grinding mill 10 pulverizing it between the rotating grinding cylinder *d* and the stationary mill casing *d*². The pulverized material is then supplied to the disc *e* 15 annularly and concentrically to the axis of the said disc *e* over a frusto-conical projection *d*¹. The quantity of dusting material may be controlled in a manner usual with distributors of dusting material by mechanically influencing the efficiency of delivery of the rolls *b* and *c* provided within the store tank *a* or other suitable means. 20 Naturally the feeding device as well as the centrifugal disc may be driven by the traversing wheels of the bogie wagon as known in connection with other distributors of dusting material.

Having now particularly described the nature 25 of my invention and the manner in which it is to be performed what I wish to have covered by Letters Patent is:

1. In a vehicle for the uniform distribution of spreadable materials, a traveling frame, a circular 30 disc mounted upon said frame for revolution in a horizontal plane and for a peripheral distribution of said materials, means to feed the latter onto said disc, a stationary inverted cup-shaped disc, circumferentially surrounding the same and provided with a rim extending downwardly to a plane beneath said disc whereby an annular space is formed between the said rim and said disc, said baffle wall being composed of two oppositely 35 located, equal semi-elliptical portions forming along their major axis opposite edges at their two intersecting faces, said axis connecting the two opposite edges extending substantially transversely at a right angle to the direction of movement of said vehicle.

2. In a vehicle for the uniform distribution of spreadable materials, a traveling frame, a circular disc mounted upon said frame for revolution in a horizontal plane and for a peripheral distribution of said materials, means to feed the latter onto said disc, a stationary inverted cup-shaped baffle wall coaxially located above said revolvable disc, circumferentially surrounding the same and provided with a rim extending downwardly to a plane beneath said disc whereby an annular space is formed between the said rim and said disc, said baffle wall being composed of two oppositely located, equal semi-elliptical portions forming along their major axis opposite edges at their two intersecting faces, said axis connecting the two opposite edges extending substantially transversely at a right angle to the direction of movement of said vehicle, the circumferential base line of said baffle wall connecting the points of 40 45 50 55 60 65 70 75 intersection of consecutive tangents bordering on

said circular revoluble disc at equally spaced points and parallel lines equalling in number said tangents and equally distributed between the opposite edges of said baffle wall.
